UNITED STATES PATENT OFFICE.

HENRY D. SCHALL AND RANSOM W. DAVENPORT, OF DETROIT, MICHIGAN, ASSIGNEES
TO DETROIT STOVE WORKS, OF DETROIT, MICHIGAN, A CORPORATION OF MICHIGAN.

OVEN-BURNER UNIT FOR GAS-STOVES.

1,289,555.

Specification of Letters Patent.

Patented Dec. 31, 1918.

Original application filed January 31, 1916, Serial No. 75,417. Divided and this application filed June 3, 1918. Serial No. 237,964.

To all whom it may concern:

Be it known that we, HENRY D. SCHALL and RANSOM W. DAVENPORT, both citizens of the United States of America, both residing at Detroit, in the county of Wayne and State of Michigan, have invented certain new and useful Improvements in Oven-Burner Units for Gas-Stoves, of which the following is a specification, reference being had therein to

10 the accompanying drawing.

The invention relates to gas stoves and in its broader features the present application forms a divisional case of an earlier application Serial No. 75,417, filed January 31, 15 1916. The invention also comprises certain improved features as hereinafter set forth.

In the drawings:

Figure 1 is a perspective view of a gas range to which our improvements are applied;

Fig. 2 is a sectional plan thereof;

Fig. 3 is a longitudinal section through the lighter for the burner;

Fig. 4 is a cross section thereof;

25 Fig. 5 is a sectional plan view showing a modified construction of lighter; and

Fig. 6 is a plan view of the range showing another modification.

In the present state of the art with certain 30 types of gas range it is customary to use a single burner for heating the bottom of one oven and the top of the broiler or toaster oven. To distribute the heat uniformly over the bottom area it is usual to have a 35 plurality of burner tubes in the form of a U-tube or otherwise connected to be controlled from a single burner. This, however, has the disadvantage that it is difficult to obtain a low fire on account of the 40 large open jet area. In other types of range a plurality of burner tubes having independent controlling valves have been used for the oven, but these burners are either supplied with gas from a manifold extending 45 along the end of the oven or from one in front adjacent to the oven door. The first is objectionable in that the manifold and burners at the end of the oven increases the longitudinal dimension of the stove by several 50 inches, and furthermore requires space at the end of the stove for access to the burners. Still another objection is that to light the burners it is necessary to provide a lighter

and usually this is supplied with gas from an independent valve also located at the end 55 of the oven. The front manifold is undesirable as the hot air from the oven when entering the mixing tube interferes with proper combustion in the burner, while the door when dropped interferes with access 60 to the valve.

It is the object of the present invention to provide a construction of oven burner unit which is applicable to a gas range having ovens and an adjacent open top section, 65 said unit comprising a plurality of burner sections having independent controlling valves, and valves being located upon the manifold at the front of the open top and in alinement with the valves controlling the 70 open top burners. The unit is further provided with a lighter which derives its gas from the burner sections, dispensing with the necessity of any independent source of supply or independent controlling valve. 75 Still further, the construction is such that the gas is conveyed to the independent burner sections through tubes located in the burner box beneath the open top section and entering the oven section through the side 80 wall thereof. Thus the construction is one which overcomes serious objections to the various constructions heretofore used, such for instance as the danger of explosion of 85 gas escaping from an unlighted burner section while another lighted section is in use, and also the difficulty of obtaining sufficiently low heat where a single burner is used. With our construction one section of the burner will be automatically lighted 90 from the other so that either or both of the sections may be used without danger, and a perfect regulation of the heat obtained.

As shown, A is the frame of the stove. B is the open top section, C is the baking oven 95 arranged at one side of the open top and above the same, and D is the lower or broiler oven beneath the oven C and at the side of the pan or casing beneath the open top. The ovens C and D are separated from each 100 other by a sheet-metal partition E which is removable when desired to throw both compartments into one. At the front of the open top section is arranged the usual gas supply tube or manifold F for feeding a 105 series of burners G G', etc., controlled by

valves H H' , etc. The valves H^4 and H^6 for controlling the broiler and oven burner are also arranged in connection with the tube and in alignment with the valves for the 5 open top burners at the end adjacent to the oven. Our improved burner unit comprises a plurality of sections extending transversely of the oven or parallel to the front thereof and independently supplied with gas from the valves H^4 and H^6 ; also a lighter which extends between said sections and to the front where it may be conveniently lighted, the gas being supplied from the burners.

In detail, and as shown in Figs. 1 to 4, I 15 and I' are gas tubes leading from the air mixing chamber J into the burner box beneath the open top section of the range and then extending laterally at K and K' through the side wall of the oven and connecting therein with burner sections M and M' . The opposite ends of these burners are supported upon a bracket N , while the tubes I and I' in passing into the oven are supported on the slotted plate O and clamped 20 by a thumb screw P at the side of the oven wall. The thumb screw passing through a slot P' in the plate which permits of a longitudinal adjustment thereof, the purpose of which is to engage and disengage the ends of 25 the tubes I and I' and the nozzles of their respective gas valves. The lighter tube Q , as shown in Figs. 1 to 4, extends centrally from one burner to the other and extends forward in the oven to the front thereof. 30 This tube Q is preferably a cored casting having apertures R R' therein for engaging upwardly-projecting nipples S on the burners M and M' , thereby forming a gas connection. There is also a slit T formed by 35 sawing which extends longitudinally of the tube Q so that by igniting the gas at the front of the tube the flame will run along the slit to each of the burners M and M' . Also this tube operates to automatically 40 light one burner from the other.

In the modified construction shown in Fig. 5, two separate gas passages Q' and Q^2 are connected respectively to the burner sections M and M' and extend adjacent to each other 45 to the front where the lighting of one will insure lighting of the other, the construction being otherwise the same as previously described.

In the construction shown in Fig. 6, in place of the single lighter tube first described or the double lighter tube shown in Fig. 5, a lighter is formed of a section extending between the forward and rear burner sections and having gas communication with the latter, while another section of the lighter extends forward to the oven front and is in gas communication with the forward burner section. These lighter sections are also preferably provided with jet openings therein 60 instead of the slot, said openings being suf-

ficiently near to each other to cause the flame to travel from one to another. This construction is also preferably an integral casting forming both the burner sections and the lighter section.

In use, whenever it is desired to light the oven burner the valve H^6 is opened and a lighted match applied to the forward end of the lighter. The gas from the valve H^6 will pass through the mixer J and tube I' to the forward burner M , from which it will pass into the forward section of the lighter tube and will be ignited at the front. The flame will then travel back to the burner section and light the same. If it is desired to increase the heat the valve H^4 is opened and the gas passing through the tube I into the burner section M' will also fill the section of the lighter between the two burners and will be lighted by the forward burner, thereby carrying the flame backward to the rear burner. After the rear burner is lighted, if so desired, the forward burner may be turned out so that the operator is free to use either or both of the burner sections without any danger of escaping gas from the section not in use.

The placing of all of the controlling valves in connection with a single manifold and arranged at the front of the open top section of the range is not only of great convenience but also adds greatly to the appearance of the stove. Again, in this position none of the burners will be disturbed by heated air or by the opening or closing of the oven door, as is the case with many stove constructions heretofore used.

What we claim as our invention is:

1. An oven burner unit, comprising a plurality of spaced independently controlled burner portions, and a lighter extending transversely to said burner portions from a point remote therefrom to each thereof, said lighter being a substantially closed tube receiving gas from said burner portions and provided with restricted flame propagating openings.

2. An oven burner unit, comprising a plurality of parallelly-arranged transversely-extending burner portions, each provided with an independent gas supply conduit at one end thereof and said conduits extending in the same plane to a point forward of each portion, and a lighter extending from a point also forward of said burner portions to each thereof, being supplied with gas therefrom and provided with restricted flame propagating openings.

3. An oven burner unit, comprising a plurality of parallelly-arranged transversely-extending burner sections, gas supply tubes for said sections in the same plane therewith and extending at substantially right angles thereto, and a lighter tube extending between said burner sections and forward

thereof in the direction of said gas supply tubes, said lighter tube receiving gas from said burner sections.

4. An oven burner unit, comprising a plurality of parallelly-arranged transversely-extending burner sections, a gas supply tube extending from one end of each of said sections and bent to extend forward at substantially right angles to and in the same 10 plane as said burner sections, and a lighter extending between said burner sections centrally thereof and forward in the direction of said gas supply tubes, said lighter tube receiving its gas supply from said sections.
- 15 5. An oven burner unit, comprising parallelly - arranged transversely - extending burner sections, gas supply tubes for said sections respectively extending from one end of each and bent to extend forward in the 20 same plane to the front and parallel to each other, and a lighter extending centrally between said burner tubes and to the front thereof and having gas connection therewith.
- 25 6. An oven burner unit, comprising a pair of L-shaped tubes having parallel transversely - extending portions constituting burner sections and angling sections constituting independent supply conduits for said burner sections terminating in mixing chambers 30 in transverse alinement with each other, and a lighter tube centrally connecting said burner sections and extending forward therefrom, said lighter tube receiving gas supply from said burner sections.
- 35 7. An oven burner unit, comprising a plurality of spaced independently controlled burner portions, and a lighter extending

transversely of said portions from a point beyond the same to each thereof, said lighter having non-communicating conduits 40 supplied with gas from the respective burner portions with restricted openings for the propagation of flame from one to the other.

8. An oven burner unit, comprising a plurality of spaced independently controlled 45 burner portions, and a lighter extending transversely between said sections and to a point beyond the same, said lighter having non-communicating conduits receiving gas from the respective burner portions and 50 provided with restricted openings for the propagation of flame from one to the other.

9. The combination with a stove having an open-top section with a gas manifold in front thereof, and an oven section at one 55 side of said open-top section and beyond said gas manifold, of an oven burner unit comprising a plurality of transversely-extending burner portions, gas supply tubes for the respective burner portions extending through 60 the side of said oven and forward into operative relation to said gas manifold, and a lighter extending between said burner portions and beyond the same to the front of 65 the oven, said lighter having non-communicating conduits supplied with gas from the respective burner portions and being provided with restricted openings for the propagation of flame from the forward end to each of said burner portions. 70

In testimony whereof we affix our signatures.

HENRY D. SCHALL.
RANSOM W. DAVENPORT.
